INVENTOR
Harry L. Wilt.

UNITED STATES PATENT OFFICE.

HARRY L. WILT, OF KANSAS CITY, MISSOURI.

OVERSOLE.

1,245,847.

Specification of Letters Patent.

Patented Nov. 6, 1917.

Application filed April 26, 1916. Serial No. 93,721.

To all whom it may concern:

Be it known that I, HARRY L. WILT, a citizen of the United States, residing at Kansas City, in the county of Jackson and 5 State of Missouri, have invented certain new and useful Improvements in Oversoles, of which the following is a specification.

This invention has relation to oversoles for shoes and an object of the invention is 10 to provide a shoe sole of durable material which is adapted to cover the sole of a shoe for the purpose of preventing wear of the shoesole, and for other purposes which will be obvious as the nature of my invention is 15 more fully disclosed.

Another object of the invention is to provide an oversole of the character described having a novel form of means for securing the oversole to the edges of the shoesole.

20 In addition to the foregoing, my invention comprehends improvements in the details of construction and arrangement of parts, to be hereinafter described and particularly pointed out in the appended claim.

25 In the accompanying drawings in which similar and corresponding parts are designated by the same characters of reference throughout the several views in which they appear;

30 Figure 1 is a view in side elevation of a shoe illustrating the application of my invention.

Fig. 2 is a view of my oversole in plan, with parts broken away, and

35 Fig. 3 is a transverse section on the line 3—3 of Fig. 2.

With reference to the drawings, 1 indicates a shoe indicated conventionally and having the usual heel 2 and sole 3. The 40 oversole comprises in its essentials a sole 4, shaped to conform to the sole of a shoe and provided upon its upper surface with a lining formed of a double thickness of material designated 5, and which is curved 45 inwardly at the edges of the sole 4 to engage the edge of the shoe sole, as indicated at 6.

The material composing the oversole is necessarily flexible, and I therefore provide 50 a reinforcing means which may also serve to secure the oversole more firmly to the shoe. The reinforcement comprises a substantially cruciform metallic plate comprising a portion 7 which extends longitudinally 55 of the oversole and is disposed between the layers of the lining 5, and is provided with

a transverse portion 8 which is disposed at the broadest portion of the oversole. The oversole is extended rearwardly to the inner edge of the heel of the shoe and does 60 not extend under the heel, but is adapted to closely conform to the instep portion of the shoesole.

That portion of the longitudinal reinforcing strip 7, which is disposed beneath the 65 instep is provided with a transverse member 9. The terminals of the members 8 and 9, and the outer terminal of the member 7 are formed with inwardly curved portions 10, which are shown as being bent double 70 to reinforce the ends thereof. The curved terminals 10 thus conform to the inwardly curved edges 6, of the lining. The sole 4, which may be of leather or other durable material is sewed, glued or otherwise secured 75 to the lining 5, and the adjacent edges of the lining may also be glued together to form a more durable structure. Openings 11 are provided in the reinforcing members so as to insure more perfect adhesion of the 80 lining to the reinforcing members.

In view of the foregoing description, the application of the oversole to a shoe should be obvious, it being merely necessary to apply the oversole to the sole of the shoe, meanwhile bending back the curved edges 6 so as to permit the engagement thereof in the recess which usually exists at the point of connection between the welt and the upper. The sole may be removed from the shoe by 85 disengaging the edge thereof from the sole of the shoe, by the aid of a tool if necessary. The lining may be made of rubber or some such resilient material which will become tightened around the shoesole and thus more securely hold the oversole in 90 place.

It will be obvious that by the use of this device the wear of the shoesole may be entirely prevented, and is particularly applicable for use by workmen whose shoes are ordinarily subjected to excessive wear. The sole may furthermore be made of wood so as to protect the shoes of persons who in their occupations are obliged to walk upon damp ground, or floors flowing with salt water such as in ice houses, confectioners, etc. The sole may also be made of rubber for use by electricians or those desiring insulated shoes.

100 While I have illustrated my invention with some degree of particularity, I realize 105

that in practice various alterations thereof may be made, such as the substitution of a cord or the like provided in the curved edge of the lining for securing the same to the 5 shoe, or other securing means. I therefore reserve the right and privilege of changing the form of the details of construction or arrangement of parts without departing from the spirit of the invention or the scope of the 10 appended claim.

Having thus fully described my invention what I claim as new and desire to secure by Letters Patent is:—

An over sole including a sole portion, a 15 lining formed of elastic material secured to the upper face of the sole portion, the edges of the lining being curved inwardly to engage the edges of a shoe sole, and a reinforcing metallic strip embedded in the lin-

ing having one terminal curved inwardly to 20 engage the toe portion of the shoe sole, the opposite terminal of the strip having oppositely extended lateral portions having terminals embedded in the lining to engage the instep portion of the shoe sole, and an integrally formed transverse portion formed 25 at an intermediate portion of the strip with the terminals thereof bent inward and embedded in the lining to engage the edges of the lining over opposite sides of the shoe 30 sole at the widest point thereof.

In testimony whereof I affix my signature in presence of two witnesses.

HARRY L. WILT.
